[57] CLAIM

The ornamental design for a mouth-touching bowstring-held anchor nock for archery, as shown.

DESCRIPTION

FIG. 1 is a top plan view of a mouth-touching bowstring-held anchor nock for archery embodying my new design;

FIG. 2 is an outside elevational view of said design;

FIG. 3 is an inside elevational view thereof;

FIG. 4 is a front elevational view thereof;

FIG. 5 is a rear elevational view thereof.

FIG. 2

FIG. 1

FIG. 3

FIG. 4
